DICTATING MACHINE TRANSCRIBER
CABINETAnthony C. De Napoli, Jr., Windsor, Conn., and
Raymond Spilman, Yonkers, N. Y.

Application October 20, 1949, Serial No. 5,598

Term of patent 14 years

(Cl. D26—14)

To all whom it may concern:

Be it known that we, Anthony C. De Napoli, Jr. and Raymond Spilman, citizens of the United States, residing in Windsor, Connecticut, and Yonkers, New York, respectively, have invented a new, original, and ornamental Design for a Dictating Machine Cabinet, of which the following is a specification, reference being had to the accompanying drawing, forming part thereof.

Fig. 1 is a front view of the dictating machine transcriber cabinet in operating position, showing our new design.

Fig. 2 is a side view of the same, looking from the left of Fig. 1.

Fig. 3 is a top view of the same, with the cabinet entirely closed.

Fig. 4 is a side view of the same, looking from the right of Fig. 1.

We claim:

The ornamental design for a dictating machine transcriber cabinet, as shown.

ANTHONY C. DE NAPOLI, JR.
RAYMOND SPILMAN.
